UNITED STATES PATENT OFFICE.

DAVID KENNEDY, OF GUELPH, ONTARIO, CANADA.

CLEAN-OUT FOR CLOSET-BOWLS.

1,287,042.

Specification of Letters Patent. Patented Dec. 10, 1918.

Application filed May 17, 1918. Serial No. 235,122.

To all whom it may concern:

Be it known that I, DAVID KENNEDY, of the city of Guelph, in the county of Wellington, in the Province of Ontario, Canada, have invented certain new and useful Improvements in Clean-Outs for Closet-Bowls, of which the following is the specification.

My invention relates to improvements in cleanouts for closet bowls and the object of the invention is to devise simple means whereby the narrow portion or neck of the discharge passage of a closet bowl may be readily gotten at when clogged so that the obstruction can be removed and it consists essentially of the following arrangement and construction of parts as hereinafter more particularly explained.

Figure 1, is a side elevation of a closet bowl partially broken away to exhibit the neck of the discharge orifice and my clean-out therefor.

Fig. 2, is an enlarged perspective sectional detail of that portion of the closet bowl containing the cleanout orifice and my closure for such orifice.

Fig. 3, is a sectional detail through that portion of the closet bowl shown in Fig. 2 and showing my closure for the orifice in full with the cover plate and nut in section.

In the drawings like characters of reference indicate corresponding parts in the various figures.

1 indicates a closet bowl. 1^x indicates a discharge orifice which is provided in the usual way with a neck 1' which forms a sharp turn in the front of the bowl and is liable to become clogged. When such passage becomes clogged it is difficult under ordinary circumstances to get the passage clear when an obstruction takes place in the neck of the passage. In order to overcome this difficulty I have provided a cleanout orifice 2 in the front portion of the bowl leading into the passage 1^x. The inner end

of the orifice is provided with a surrounding recess 2^x. 3 indicates a curved plate substantially oval in form and fitting at its edges within the recess 2^x. The center of the plate 3 is provided with a boss 3^x which fits the cleanout orifice 2. 3' indicates a stem extending outwardly from the center of the boss 3^x. The stem 3' is externally threaded and at its end is provided with an internally threaded orifice 3². 4 indicates a cover plate provided with an orifice 4^x through which the stem 3' extends. 5 indi-

cates a securing nut which is threaded on to the stem 3' against the cover plate 4. 6 indicates an eye bolt which has a threaded stem screwed into the orifice 3². 7 indicates a cord or chain connecting at one end to the eye of the eye bolt 6 and at the opposite end to a suitable securing device such as a staple 9.

When it is desired to clean out the passage 1^x the nut 5 is unscrewed from the stem 3' and is passed over the eye of the eye bolt 6 and over the cord 7. The plate 4 is similarly removed. The plate 3 and boss 3^x and stem 3' formed integrally are then forced inwardly into the passage, the cord 7 preventing the plate 3 and connected parts from passing down the discharge orifice. It will be noted that the plate 3 and parts formed integrally therewith are oval, the orifice 2 being also oval. When the plate is released as above described and forced inwardly into the passageway it is given a quarter turn so as to allow it to pass out through the orifice, it being held by the cord 7 from passing down the passageway during this operation. The obstruction may then be removed by a suitable instrument. When the passage is cleared the plate 3 and parts connected thereto may be drawn back into position by the cord 7, the plate 4 returned to its place and the nut 5 screwed on to the stem 3', securing the parts together.

In order to make the device water and sewer gas tight a very thin layer of putty is put in the recess formed around the orifice 2 before putting in the plate 3. By pulling the plate tight up into place and seating it against the putty a perfectly tight joint is formed.

From this description it will be seen that I have devised a very simple means whereby a cleanout orifice may be cleared of an obstruction gathered in the neck portion thereof which is otherwise difficult to clear.

What I claim as my invention is.

1. The combination with the closet bowl and discharge passage thereof having an orifice formed in the wall of the bowl leading into the discharge passage, of a closure for the orifice comprising a member fitting into the orifice and provided at its inner end with an outwardly extending flange overlapping the edges of the orifice, a stem extending outwardly from the closure, means for securing the closure in place, and means for preventing the closure from passing

down the discharge passage when such securing means is removed.

2. The combination with the closet bowl and discharge passage thereof having an orifice formed in the wall of the bowl leading into the discharge passage, of a closure for the orifice comprising a member fitting into the orifice and provided at its inner end with an outwardly extending flange overlapping the edges of the orifice, a stem extending outwardly from the closure, means for securing the closure in place, an eye located at the end of the stem, a cord connected to the eye at one end and secured to permanent securing means at the opposite end.

3. The combination with the closet bowl and discharge passage thereof having an orifice formed in the wall of the bowl leading into the discharge passage, of a closure for the orifice comprising a member fitting into the orifice and provided at its inner end with an outwardly extending flange overlapping the edges of the orifice, a stem extending outwardly from the closure, means for securing the closure in place, an eye located at the end of the stem, a cord con-

nected to the eye at one end and secured to permanent securing means at the opposite end, and a cover plate having an orifice 30 through which the eye is designed to pass, and a nut adapted to be screwed on to the stem against the cover plate.

4. The combination with the closet bowl and discharge passage thereof having an 35 orifice formed in the wall of the bowl leading into the discharge passage, of a closure for the orifice comprising a member fitting into the orifice and provided at its inner end with an outwardly extending flange overlapping the edges of the orifice, a stem extending outwardly from the closure, means for securing the closure in place, an eye provided with a threaded stem adapted to be screwed into an internally threaded ori- 40 fice formed in the stem of the closure, and a cord connected to the eye at one end and secured to permanent securing means at the opposite end.

DAVID KENNEDY.
